UNITED STATES PATENT OFFICE

PAUL M. PINCKARD, OF BIRMINGHAM, ALABAMA

BY-PRODUCT COKE OVEN

Application filed June 24, 1930. Serial No. 463,485.

This invention relates to certain new and novel improvements in by-product coke ovens, and the primary object of this invention is to provide in an oven of the above mentioned character auxiliary passages in the charging hole of the by-product coke oven, and means intermittently placed between charging holes and the standpipe to provide auxiliary passages in present-day by-product coke oven structures, the passages intended for collection of gas through said charging holes and passages and at the same time to maintain a flow of gas over the leveled charge of coal in the coke chamber to stand-pipe.

Other objects and advantages of the invention will become apparent during a study of the following description taken in connection with the accompanying drawings:

Figure 1 is a vertical longitudinal sectional view taken through a coke oven for more clearly illustrating the invention as applied thereto.

Figure 2 is a fragmentary detail sectional view taken through the charging passages and the auxiliary passages which communicate with the former.

Figure 3 is a view similar to Figure 2, showing the modified form of buffer discharging passage.

With reference more in detail to the drawings, it will be seen that I have designated the oven generally by the reference character O, the same being provided with the bottom or level end thereof with the usual coke chamber designated generally by the reference character C.

The top wall of the coke chamber is designated generally by the reference character W. As is well known in the art, the top wall of the coke chamber of a by-product coke oven, is provided with a plurality of openings better known in the art as charging holes through which coal is passed downwardly to the coke chamber of the oven. Abutting the

present invention is the wall W of the coke oven and wherein the top thereof is provided with usual plurality of longitudinally spaced charging holes 5.

Holes 5 with the chamber C are a plurality of charging passages which extend vertically through the wall W. The charging passages altho really one vertical passage to coke chamber are designated each as in pairs for convenience of description of cross sectional view in relation to passages 9 that may be designated as auxiliary collecting passages, each pair so designated including an upper passage 6 and a lower passage 7 in longitudinal alignment with the upper passage 6. 60 Passage 6, as is apparent at its upper end, opens into, or at its registry with the hole 5 in the wall W, while the lower passage 7 at its lower end opens inwardly to the chamber C. 65

As is also known in the art, there extends through the wall W at one end thereof, and in vertical spaced relation to the charging passages, a standpipe which in the present instance, is designated, by the reference character 8. The standpipe 8 which extends vertically through the walls W, has its lower open end indicating with the chamber C, and at its upper end the standpipe 8 projects beyond the top or upper face of the wall W. 75

At each end there is provided an elongated longitudinally extending passage 9, formed in the wall W extending longitudinally of the wall parallel to the chamber C. The passages 9 which may be designated as 80 auxiliary collection passages extends between the upper and lower passages 6 and 7 of the pairs of passages, the upper passage 6 of said pairs of passages, opening into the passages 9 at the bottom of the passage 6 and the lower passage 7, opening at its upper end into the bottom of the passages 9. 85

The passages 9 at that end farthest remote from the standpipe 8 is of course closed while the passage at its open end the same 90.

passage 9 is opened into standpipe 8, laterally of the pipe, as in Figure 1.

From the foregoing then, it will be seen that coal may be passed through the holes 5, and the pairs of passages 6 and 7 leading therefrom in the chamber C to seek the desired level without stoppage by coal of passages 9 so that passages 9 can function during coking process as intended by this invention.

During the operation of the oven, the passages 9 in conjunction with the charging passages 7 provides a by-pass from the chamber C to the standpipe 8 so that parts of the occluded gas will be conveyed therethrough to the standpipe to pass upwardly and outwardly at the open upper end of the standpipe.

Parts of the occluded gas will of course be left to be drawn over the leveled charge of the coal in the chamber C, toward that end of the chamber at which the standpipe is located to pass upwardly through the lower open end of the standpipe as is at present the case in all types of coke ovens.

The purpose of the arrangement of passages 9, to passages 6 and 7 (charging holes) is intended as an auxiliary means for carrying the gas to the standpipe and is not intended in any way to abandon entirely common practice of drawing gas over the level charge to the standpipe, but only to complement that passage.

The mouths of the passages 6 and 7 where the passages connect with the passage 9, are especially designed for protection against blocking the passage by piling coal in charging (although this piling will not occur if the leveling process is properly timed). In this connection and as shown to advantage in Figure 2, the upper passage 6 of the pair of passages at its lower end is reduced to provide a restricted discharge neck 6' which at the opened lower end of the passage 6 is cylindrical with the top of the passage 9.

In Figure 3, it will be seen that the passage 6 at the lower end thereof, is substantially the same in diameter at its discharge mouth 6a as at any other point in the length of the passage, in other words, the passage 6 being of uniform diameter from its lower to its upper end but of less diameter than passage at 7.

In regard to the mouth of the passage 7, at the upper end of the passage, the mouth is flared as at 7' as is evident from a study of Figures 2 and 3, irrespective of whether the passage 6 be of uniform diameter throughout its length as in Figure 3, or having a fixed mouth 6' as in Figure 2.

It is thought that from the foregoing description, taken in connection with the accompanying drawings, a clear understanding of the operation, advantages and utility of an invention of this character will be had by those skilled in the art, without a more detailed description.

Further, it is thought that those skilled in the art will appreciate such advantages as accrue from the provision of such auxiliary passages forming the by-pass of the chamber to the stand-pipe, as for example, such by-pass will result in less time in hot zone for richest gas will eliminate extreme pressure caused by faulty leveling, will afford better care of gas at the time occluded gas is at approximate maximum volume and distance from level coal to roof of oven is least; namely a new charge. It can readily be seen by those skilled in the art, that gas, so by-passed through charging holes and designated auxiliary collecting passages will have shorter distance to travel in hot zone, and will thus never reach as high an initial temperature. Furthermore such an arrangement of a by-pass will eliminate much of the gas travel from ovens to flues which at present is excessive on new charges, due to the built-up pressure, and which not only cools the flues and causes a latent heat loss to stack, but represents a loss of gas to stack as well as a loss of gas through doors and jambs. Furthermore the very elimination of these losses means near compliance with various smoke nuisance laws.

Furthermore this arrangement of a by-pass will in all probability result in less ammonia broken up to cyanides, less condensed polymerization of benzol to naphthalene by heat and further to permit of cooler gas delivered to the gooseneck. (The gooseneck as is well known is connected between the standpipe), otherwise known as an ascension pipe and collecting main.

Even though I have herein shown and described the preferred embodiment of my invention, it is to be understood that the same is susceptible to changes fully comprehended by the spirit of the claims as herein described, and the scope of the appended claims.

Having thus described my invention, what I claim as new is:—

1. In combination with a coking chamber and a stand pipe connected therewith, a by-pass for gases leading from the coking chamber to the stand pipe and having lateral branches providing coal charging passages for the coking chamber; the by-pass and branches being arranged in the roof of the coking chamber.

2. In combination with a coking chamber and a stand pipe communicating therewith, a passage for gases leading laterally from the stand pipe and having vertical branches providing coal charging passages for the coking chamber, said passage and vertical branches being arranged in the roof of said coking chamber.

3. In combination, a coking chamber, a stand pipe communicating therewith, a horizontal passage for gases leading from said

stand pipe and having vertical branches leading to said chamber, said passage and branches being arranged in the roof of said chamber, and said branches having upper ends opening outwardly of the chamber and lower ends opening into said chamber whereby to provide coal charging passages for said chamber.

In testimony whereof I affix my signature.

PAUL M. PINCKARD.
